UNITED STATES PATENT OFFICE.

THOMAS SOUTHGATE, OF LONDON, ASSIGNOR TO THOMAS WILLIAM WEBLEY
AND HENRY WEBLEY, OF BIRMINGHAM, ENGLAND.

MECHANISM FOR BREECH-LOADING SMALL-ARMS.

SPECIFICATION forming part of Letters Patent No. 443,635, dated December 30, 1890.

Application filed March 22, 1890. Serial No. 344,940. (No model.)

To all whom it may concern:

Be it known that I, THOMAS SOUTHGATE, a citizen of England, residing at 6 Burton Crescent, London, England, have invented new 5 and useful Improvements in Ejector Mechanism for Breech-Loading Small-Arms, of which the following is a specification.

My invention relates to certain improvements 10 in the ejector mechanism for single and double barreled breech-loading small-arms.

My improved ejector mechanism consists 15 of an ejector-tumbler acting upon the extractor, and of an ejector-spring in the fore end, a projection on the firing-tumbler having a bent cut in it, and a sliding bar having a spring to act upon it in a manner to be described. This sliding bar forms the means 20 of communication between the firing and ejecting tumblers. The object of the spring is to obviate the necessity of moving the sliding bar by the fall of the firing-tumbler, which is objectionable, because such moving of the sliding rod by the fall of the firing-tumbler lessens the blow given by the said tumblers 25 to the striker. I cause the spring to hold the bar always as far forward as the ejector-tumbler will allow, and therefore out of the way 30 of the projection on the firing-tumbler at the moment of firing. The sliding bar may be modified in form to suit different types of actions, but its function is always the same—namely, to act as a means of communication 35 between the firing and ejecting tumblers. The ejector-tumbler is of the following form: reaching upward and acting upon the extractor is a long arm, which is circular at the front, and this circular front is cut away at a sharp angle toward the axis of the tumbler. Reaching downward is a short arm which is 40 made circular on the back so as to form a cam. The sliding rod is held against this circular back of the short arm of the ejector-tumbler by the spring which I cause to act upon the sliding rod. The free end of the 45 ejector-spring bears on the circular front of the ejector-tumbler, except at the moment of ejection, when the spring takes onto the flat part, giving the said ejector-tumbler a sudden jerk round. With my improved ejector

mechanism no sear or sear-spring is required, 50 neither is an injector-cam required, as the ejector-tumbler fulfills the office of the ordinary extractor-cam in addition to acting as an ejector-tumbler when the gun has been fired.

My invention will be understood by reference 55 to the accompanying drawings.

Figures I and II show my invention as applied to side-lock guns, and Figs. III and IV show the application of my invention to the Anson-Deeley type of gun. 60

In Fig. I the gun is shown as having been fired and in Fig. II as having been opened after firing, and the various parts of the mechanism are shown separately under Fig. I.

The sliding bar *a* is pressed forward by the 65 spring *g* and held against the ejector-tumbler *c*. The spring *g* takes its abutment against the nut *h*, through which the bar is free to move longitudinally with also a slight amount of freedom in a vertical direction. 70

On the firing-tumbler is a projection *b*, having a bent *b'* cut in it. The bar *a* extends from this projection *b* to the ejector-tumbler *c*. It will be seen that the bar *a*, being held forward by the spring *g*, is never moved by 75 the fall of the firing-tumbler.

On opening the gun after firing the following operations ensue: As the barrels are turned downward the bar *a* will be jammed between the short arm of the ejector-tumbler *c* and the 80 projection *b* on the firing-tumbler, and therefore as the firing-tumbler is being cocked the bar *a* will be carried slightly upward, and thus prevented from sliding into the bent *b'* in the projection *b* on the firing-tumbler. 85 Therefore the bar *a* is held forward by the projection *b* during the whole time of opening the gun. The bar *a*, being thus held forward, will cause the ejector-tumbler *c* to turn on its axis, and as a first result the extractor 90 *f* will be pushed backward. While this movement is taking place the rotation of the ejector-tumbler *c* on its axis causes the end of the spring *d* to slide along the circular part of the ejector-tumbler toward the flat part. 95 When the spring *d* reaches the flat part of the ejector-tumbler *c*, it causes the said tumbler to be jerked round, giving the extractor the

required sudden impulse needed for ejection of the cartridge-case. These movements are so timed that the act of ejection takes place when the chamber of the barrel has risen clear 5 of the standing-breech. Should the gun be opened with the firing-tumbler at full-cock, the bar *a* will be pushed back into the bent *b'* in the projection *b*, and as a result the ejector-tumbler *c* will be turned far enough 10 on its axis to press back the extractor to the unloading position, but not far enough to bring the spring *d* to act on the flat part of the ejector-tumbler *c*. Therefore no ejection 15 of the cartridge will take place.

15 Figs. III and IV show my improved ejector mechanism as applied to the Anson-Deeley type of action. Fig. III shows the gun closed and fired, and Fig. IV shows the gun as opened after firing. The parts of the mechanism are 20 also shown separately.

Similar parts in Figs. III and IV bear the same letters of reference as in Figs. I and II. It will be observed that the projection *b*, with the bent *b'* on the firing-tumbler, the 25 ejector-tumbler *c*, and the ejector-spring *d*, are similar to those already described; but the bar *a* is modified in form, as is also the spring for actuating the same. The sliding bar *a*, as before, reaches from the projection *b* on the 30 firing-tumbler to the ejecting-tumbler *c*. Attached to the bar *a* is a spring *g*, of the form shown, bearing against the stud *h*. This spring holds the bar *a* downward and also presses it forward against the ejecting-tumbler *c*. The 35 gun having been fired and the mechanism being in the position shown in Fig. III, on opening the gun ejection will ensue by a series of movements exactly analogous to those described in relation to Figs. I and II—that is 40 to say, the resistance of the bar *a* abutting against the projection *b* will turn the ejector-tumbler first to the unloading position of the extractor, and then bringing the ejector-spring onto the flat part of the ejector-tumbler will 45 cause the extractor to receive the sudden impulse which causes ejection of the cartridge-case, and the parts will then be in the position

shown in Fig. IV. Should the gun be opened with the firing-tumbler at full-cock, no ejecting action will ensue, as previously described. 50 On closing the gun the parts will assume the position shown in Fig. III, except that the firing-tumbler will be at full-cock and the rear end of the bar *a* will be opposite the bent *b'*.

The spring *g* may be omitted without affecting 55 the action of the mechanism for extraction and ejection, but the fall of the firing-tumbler would be slightly impeded by the bar *a*.

Having thus described the nature of this 60 invention and the best means I know for carrying the same into practical effect, I claim—

The combination, with the fore-end and barrel of a breech-loading fire-arm, of a sliding extractor *f* on the barrel, the ejector-tumbler 65 *c*, pivoted on the fore-end and having a long arm above its pivot acting on the extractor, and provided with a convex front which is cut away at a sharp angle toward the pivot to form a flattened face, said tumbler also having 70 a short arm below its pivot provided with a cam-back, a spring *d* at the fore-end adapted to bear against the flattened face of the tumbler for imparting the ejecting impulse to the extractor, the sliding bar *a*, having its forward 75 end bearing against the cam back of the tumbler, and the firing-tumbler having a projection *b*, provided with a bent *b'*, to act on the rear end of the sliding bar, substantially as described.

In testimony whereof I have signed my name to this specification, in the presence of two subscribing witnesses, this 7th day of March, A. D. 1890.

THOMAS SOUTHGATE.
